POLISH REMOVER

Earl A. Erickson, Detroit, Mich.

Application May 20, 1954, Serial No. 431,156

3 Claims. (Cl. 15—21)

The invention pertains to a cosmetic appliance and more particularly to a nail cleaning apparatus for removing the polish or enamel from the finger nails.

In the use of finger nail polish and enamels, the individual frequently wishes to remove the old coating or application, either to omit it for awhile or to put on a fresh application. The old coating may have become scratched, marred or partially worn away, and the wearer may desire to apply a fresh coating of the same color or of a different color or tint. The old coating is usually removed by scrubbing the finger nails with alcohol or some other suitable solvent medium. In view of the solvent power of such a medium, spilling or spattering it upon adjacent objects, or furniture surfaces may cause damage which becomes considerable as the result of repeated operations over a period of time.

It is accordingly an object of the invention to provide apparatus for safely and conveniently removing polish or enamel from the finger nails.

It is also an object of the invention to provide a device whereby polish or enamel may be quickly removed from finger nails without the necessity of taking special care to avoid spattering or spilling the solvent medium upon furniture and nearby articles.

It is a further object of the invention to provide finger nail cleaning apparatus which serves also as a container for storing a quantity of the solvent medium safely enclosed to prevent combustion or vaporization while being at all times conveniently accessible for prompt use.

Another object of the invention is to provide such a polish removing device in a compact unit which is reliable and positive in operation and which is of a simple rugged construction convenient to manufacture, assemble and maintain.

A further object of the invention is to provide such a finger nail polish removing device made of a plastic composition or other suitable material to be of light weight and pleasing to the touch; to be made transparent, semi-transparent or translucent so that the level of the solvent may be readily seen; and to be made in a wide variety of shades or tints of color to satisfy the preferences of various individuals for an article of such a personal nature.

Further objects and advantages are within the scope of the invention, such as relate to the arrangement, operation and function of the related elements of the structure, to various details of construction and to combinations of parts, elements per se, and to economies of manufacture and numerous other features, as will be apparent from a consideration of the specification in conjunction with the drawing disclosing specific embodiments of the invention, wherein similar reference characters are applied to corresponding parts throughout, and in which:

Fig. 1 is a side elevational view showing an embodiment of the finger nail polish removing device;

Fig. 2 is a plan view thereof;

Fig. 3 is a sectional view on line 3—3 on Fig. 2;

2

Fig. 4 is a cross-sectional view as indicated by line 4—4 on Fig. 3;

Fig. 5 is a diagrammatic view illustrating the operation of the apparatus for removing polish from a finger nail, dotted lines showing the inserted finger and the motions of the scrubbing element; and

Fig. 6 is a fragmentary sectional view showing a structural variation.

Referring more specifically to the views of the drawing, I have illustratively disclosed an embodiment of my finger nail polish removing device comprising a solvent receiving and holding vessel 11. For its purpose, and intended use, the vessel is preferably provided with a laterally extending base 13 to impart greater stability to the unit.

The open top of the vessel 11 is closed by means of a cover 15 which may be provided with a reduced flange fitting snugly down inside of the vessel as the cover is pressed down thereon or threadedly connected thereto as illustrated.

The cover 15 is provided with a finger tip receiving aperture 17 for receiving and holding an inserted finger with the tip 19 in a predetermined position above the level of the solvent medium 21 in said vessel, both of which are represented by dotted lines in Fig. 5. This aperture 17 also receives the solvent medium which may be poured in to the desired depth. For closing this aperture during time intervals between useful operation of the device, a cap 23 is provided having a tapered conical plug 25 which fits snugly into this aperture to provide a sealed fit therein. The upper part of the cap is shaped to provide a knob 27 to facilitate removal when the apparatus is to be utilized, and the substantial length of the inwardly projecting plug 25 facilitates installation of the cap on the vessel 11.

Within the solvent holding chamber, so enclosed, a cleaning or scrubbing element 29 is provided. This may be a bristle brush, as shown in Figs. 3 and 4, or it may be any suitable cleaning or rubbing element curved and conformed to fit a finger nail and suitable to be dipped into the solvent and then rubbed up and down upon the nail of an inserted finger, as represented diagrammatically in Fig. 5. The scrubbing element is movably mounted on a movable support whereby it can be suitably actuated from the outside of the solvent chamber without any risk that the solvent will be spilled or spattered from the vessel.

This is readily accomplished by providing a plunger rod 31 which slides back-and-forth through a bearing aperture 32 in the cover, the scrubbing element 29 being threaded, or secured upon the inner end thereof in any suitable manner. As shown, the bearing aperture 32 is provided with a bearing sleeve 33 having its lower end secured therein, the position relative to the finger receiving aperture being such that the scrubbing element 29 on the lower end of the rod effectively scrubs the finger nail with the solvent. This bearing sleeve 33 may be threaded, cemented, or secured in the cover aperture in any suitable manner. The other or outer end of the push rod 31 projects up above the device and is exposed for convenient manual operation to scrub the nail of the inserted finger, this operation being further facilitated by means of a conveniently shaped button 35 secured on the exposed end of the slidable rod.

The upward movements of the push rod 31 and its scrubbing element in one direction may be made automatic so that the user has only to depress the button repeatedly and these elements will spring up each time the button is released. This is readily accomplished by providing in the bearing sleeve 33 an enlarged counterbore 37 opening from the upper end, inserting a compres-

sion spring 39 therein concentric to the plunger rod 31, and providing a cross-pin 41 through the rod at a suitable position to rest upon the upper end of the spring. A centrally apertured stop plug 43 is secured in the upper end of the bearing sleeve 33 to pass the sliding rod there-through.

The cover 15 may have peripheral threads to screw into the open top of the vessel 11 correspondingly threaded. But in view of the simple rugged construction of the apparatus it is not desirable or necessary to remove the cover 15 for repairs. So instead of the threaded arrangement it may be snugly sealed and secured in and upon the upper edge of the solvent holding vessel by means of any suitable cement. To charge the apparatus with the solvent medium it is only necessary to remove the cap 23 and pour the solvent therein to the desired level.

In operation, it is only necessary to remove the cap 23 and insert a finger into the enclosed chamber. Then, with the other hand, the user rapidly depresses and releases the push rod, scrubbing the fingernail with the solvent which is picked up each time the scrubbing element is pressed down toward the bottom of the vessel.

This self-contained device encloses the scrubbing operations so that the solvent 21 cannot be splattered, spattered or sprayed around on surrounding articles and furniture surfaces. Nor can it be tipped over to spill the solvent. When in use the finger aperture is substantially closed by the inserted finger, and when the operations are completed the cap 23 is reinserted and it is so snug-fitting that it prevents loss of the solvent or danger of combustion by restricting the escape of vapor from the enclosed chamber.

When the device is made of plastic composition material, it is of light weight as well as being otherwise pleasing to the touch. Another important advantage of utilizing available plastic material is that the sidewalls of the chamber may be made transparent, semi-transparent or translucent, so that the level of the solvent therein is conveniently observable. Also, in a personal article of this nature, it is important to be able to provide a wide variety of colors, tones or tints to suit the preferences of many different individuals and this requirement is also easily satisfied when the available plastic materials are utilized.

Two plastic materials which have proven satisfactory for making my polish remover are those well-known and available on the market as nylon or polyethylene, which is mentioned by way of example and without intention of so limiting the scope of the invention.

Manufacture and assembly of the device may be further simplified by making various parts integral and this is readily accomplished when the device is made of the plastic composition material, as will be readily understood. For example, the rod 31 and the pressing button 35 on the upper end, may be made integral. Or the lower end of this rod may be made integral with the scrubbing element 29, thereby reducing the number of parts to be manufactured, handled and assembled.

As Fig. 6 shows, further simplification may be accomplished by providing a rod bearing housing 33' which is

integral with the cover 15. As shown, the spring enclosing cavity 37 in the housing 33' may then be extended downward to open into the vessel, and a washer 45 is pressed snugly up thereto forming a bottom stop for the spring 39. The rod 31 passes freely up and down through this washer 45.

A washer 47 may be pressed, as a snug fit, on the upper end of the rod 31 to replace the cross-pin 41 and to eliminate the operation of drilling a corresponding transverse hole on the rod 31. This washer is then loose in the cavity 37 but fast upon the rod 31 and it presses down upon the upper end of the spring 39.

The spring 39 is preferably made of stainless steel for corrosion resistance and long life.

While I have described only a preferred embodiment of my invention by way of illustration, many modifications will occur to those skilled in the art, and I intend in the appended claims to cover all such modifications as fall within the true spirit and scope of my invention.

What I claim as new and desire to secure by Letters Patent of the United States is:

1. A nail polish remover comprising a vessel for holding a quantity of solvent, a cover member removably secured to the top of said vessel, and provided with a pair of openings therein, the portion of the cover element adjacent one of said openings constituting a finger rest for impinging beneath the first node of a person's finger, a sleeve member removably mounted within the other of said openings, a vertically reciprocal scrubbing element resiliently and freely mounted within said sleeve member, said scrubbing element being arranged to present its scrubbing surface for movement in a path adapted to vertically wipe the nail of a finger supported by the said finger rest, said vessel also being of greater depth than the length of that portion of the finger to be accommodated therein to an extent permitting a quantity of solvent to be accommodated below the finger tip, a plunger for manually depressing said scrubbing element into the lower portion of said vessel, and a spring resiliently mounting said scrubbing element within said sleeve member for returning said element to an upper position in said vessel, when manual pressure on said plunger is relieved.

2. The combination as set forth in claim 1 wherein said finger rest is of arcuate configuration.

3. The combination as set forth in claim 1 wherein the scrubbing element has a contour approximately the shape of a person's finger so as to fit snugly thereabout.
